(57) **CLAIM**

The ornamental design for a scoop-shaped mirror for motorcycles, as shown.

DESCRIPTION

FIG. 1 is a front perspective view of a scoop-shaped mirror for motorcycles according to my invention.

FIG. 2 is a rear perspective view of FIG. 1.

FIG. 3 is a front orthogonal view of FIG. 1.

FIG. 4 is a rear orthogonal view of FIG. 1; and,

FIG. 5 is a top orthogonal view of FIG. 3.
